SHAKER AND POURING DISPENSER
Donald W. Larson, Hinsdale, Ill.
(235 La Grange Road, La Grange, Ill.)
Filed Dec. 29, 1958, Ser. No. 783,501
8 Claims. (Cl. 222—189)

This invention relates to a dispensing device for containers for soap, sugar, spices or other particulate materials.

The object of the invention is to provide a dispenser of this kind having a single opening therethrough and a pair of removable covers, one perforate and one imperforate, so that particulate material may be poured out in a stream or spooned out with both covers removed or shaken out with only the imperforate cover removed.

Another object is to provide such device wherein all of the assembled elements are formed in a unitary molded body from flexible plastic, thus providing an inexpensive, unbreakable, sanitary unit.

Another object is to provide a dispensing closure construction wherein the perforate and imperforate lids or covers are conveniently hinged to the frame member and equipped with tabs to permit opening and closing both cover members without difficulty.

These and other objects of the invention will become apparent from the following description when read in connection with the accompanying drawings, wherein:

FIGURE 1 is a perspective view of a carton for particulate material having a dispensing device mounted in the top thereof;

FIGURE 2 is an enlarged plan view of the dispensing device shown in FIGURE 1 and constructed in accordance with the invention;

FIGURE 3 is a sectional view taken along the line 3—3 of FIGURE 2;

FIGURE 4 is a sectional view through the dispensing device and the top of the container in which it is mounted showing the imperforate and perforate covers in closed position;

FIGURE 5 is a sectional view taken along the line 5—5 of FIGURE 4;

FIGURE 6 shows a modified form of the dispensing device of the invention integrally molded with a cap or top for a container such as the container 10 of FIGURE 1; and

FIGURE 7 is a sectional view taken along the line 7—7 of FIGURE 6.

The dispensing device of the invention is suitable for use with a container such as that identified by the numeral 10 in FIGURE 1, having a cap or top 12 and a bottom 14 secured to the body portion. The dispenser is also suitable for use with other types of containers. Mounted in the top wall 12 is a dispensing device constructed in accordance with the invention and identified generally by the numeral 20. The device consists of a frame member 30 of substantial thickness having a groove 26 in the outer peripheral wall thereof which is adapted to receive the marginal edge of wall 12 surrounding an opening in the container top. The upper flange 30 of the frame member extends over the marginal edge of the wall 12 and may be tapered toward the outer edge. The lower portion of the outside wall of frame member 22 is tapered inwardly as indicated at 28 to facilitate pressing the dispensing unit into the opening provided therefor in the top of the container. The inner peripheral face 29 of the frame 22 also slopes toward the center of the opening to provide a seat on which the perforated cover or web 32 rests when in closed position. There is no shoulder or flange on which particulate material may rest and interfere with seating of the web. A bead 31 is provided on the inner peripheral edge of the frame member near the

2

top surface thereof. The bead serves to hold the cover or lid 48 in closed position. The frame member 22 may be elliptical, round, generally oblong with rounded corners, as illustrated in the drawing, or any other suitable shape.

Perforate web 32 containing holes 38 is hinged to the frame 22 by means of plastic strip hinges 34, 36 extending from the left side of the frame as viewed in FIGURES 1 and 2. Web 32 has an upwardly projecting side wall 42 flared outwardly toward the top (when disposed within the frame) to provide a press fit against the side wall and bead 31 of the frame. The outside corner of the projection 42 is broken to conform with the bead 31. It will be noted that the projecting side wall forms a well in web 32. This provides a pocket for the imperforate cover 48, as indicated below. A tab 40 also integrally molded from plastic material extends from the side of the cover opposite the hinged side and is provided to facilitate lifting the web or inserting the web in the frame. When the perforate web 32 is disposed within the frame and seated on its supporting flange 24, particulate material from the container may be sprinkled through the openings 38. In other words, the container may be used as a shaker. When the web 32 is removed as shown in FIGURE 1, the frame 30 defines a pouring spout through which particulate material may freely flow.

To seal the opening completely I have provided an imperforate lid or cover 48 which may be hinged to the other side of the frame 30 by means of plastic strip hinges 50, 52 similar to the hinges 34, 36. The cover 48 has a central depression in the underside thereof which results in a marginal base 54 which seals against the surface of the perforated web 32 when both are in closed position, as best shown in FIGURE 4. The cover 48 has a tab 56 similar to the tab 40 to facilitate insertion and removal thereof in the well provided in the top of perforated web 32. In order to provide a good seal between the cover 48 and the web 32, a bead 43 is provided around the inner edge of the vertical flange 42 projecting from the surface of the cover 32 as shown in FIGURE 3.

In FIGURES 6 and 7 I have shown a modified form of my invention wherein both the perforated web and the imperforate cover are hinged together from one side of the frame member. Also in this modification the frame member is integrally molded with a cap 15 having a downwardly turned flange 16 adapted to fit over the body 10 of the container (FIGURE 7). By integrally molding the dispenser in the wall of the container, the labor required for mounting the dispensing unit is eliminated. Furthermore, the integrally molded assembly is not likely to become disassembled. In FIGURES 6 and 7 the frame member is identified by the numeral 60 and has an inner face 62 inclined inwardly toward the container which provides a seat for the perforate web 66 which has a complementary inclined outer surface 73. The web 66 contains sprinkler holes or openings 67 and is hinged to the side of the frame by means of plastic strip hinges 70, 71. A marginal projection 68 extends above the plane of the perforated web 66 and provides a well for the imperforate cover 74, hinged to the other side of the perforated web 66. Projection 68 carries an internal bead 69 under which the cover is seated in closed position. The cover 74 is secured by means of hinges 76, 77 which are similar to hinges 70 and 71. The underside of the cover 74 is centrally depressed so that a marginal base 80 is formed around the outside thereof. The marginal base 80 in closed position is slightly spaced above the top of the web 66 so a granular material that might lodge thereon does not interfere with the sealing of the web 66 beneath the bead 64. A tab 78 is provided to facilitate insertion and removal of the cover 74 in the well provided therefor in the top of the perforated web 66. Similarly, a tab 72 is

provided to permit insertion and removal of the perforated web 66 within the frame 60. The upstanding projection 68 on the perforated web is slightly flared so that it forms a tight seal against the inner wall of the frame 60 as the web is pushed into place below the bead 64 near the top of the frame.

It will be appreciated that the container as shown in FIGURES 6 and 8 may be used to pour particulate material through the opening in the frame member 60. When the perforated web 66 is snapped into place within the frame the container may be used as a shaker. When the container is not in use the imperforate cover 74 is pressed down into the well provided therefor in the top of the perforated web. The bead 69 serves to hold the imperforate cover 74 securely in position. When the container is being used as a shaker the imperforate cover 74 will, of course, be disposed on the right side of the frame since it is hinged to the perforated web rather than to the frame member.

From the foregoing description it will be appreciated that the dispensing unit of the invention is designed to be molded in one piece, frame, perforated web, cover, hinges, tabs and all. Polyethylene is the preferred plastic but other flexible materials such as plasticized vinyl resins and rubbers are suitable.

Other modifications of this invention will occur to those skilled in the art. It is my intention to cover by the appended claims elements which are equivalent to those shown in the drawing as well as other modifications which may reasonably be included within their scope.

What I claim as new and desire to secure by Letters Patent of the United States is:

1. A molded plastic dispensing device for a container comprising a flat frame member having a central opening therethrough, a perforated web having a marginal edge adapted to seat within the opening in said frame and hinged thereto, an outwardly directed rim along the marginal edge of said web and forming a seat, and, a removable imperforate cover hinged to the dispensing device and seatable in the rim of the perforated web.

2. A unitary molded plastic dispensing device for a container comprising a flat frame having an opening therethrough, a perforated web adapted to seat in the opening of said frame and hinged to one side thereof, a peripheral rim on the outside of said perforated web, and an imperforate cover hinged to the other side of said frame and seatable within the peripheral rim of said web.

3. A unitary molded plastic dispensing device for a container comprising a flat frame having an opening therethrough, a perforated web adapted to seat in said opening of said frame and hinged to one side thereof, a tab extending from the side of said web opposite said hinged side, a peripheral rim around the outside of said web, and an imperforate cover hinged to the other side of said frame and seatable within the rim of said web.

4. A unitary molded plastic dispensing device for a container comprising a flat frame member of substantial thickness having a groove in the outer peripheral side wall thereof for receiving the container wall in which it is mounted, a through opening said frame having an inner peripheral face inclined inwardly toward the container, a perforated web having a marginal projection extending upwardly therefrom and defining a well, said web being hinged to one side of said frame and adapted to seat on said inner face, a tab extending from the side of said web opposite said hinged side for removing the web from the frame, a removable imperforate cover hinged to the device and adapted to fit within said well to seal off said perforated web.

5. The device of claim 4 wherein said marginal projection and said frame each carry a bead on its inner peripheral wall near the top thereof to removably secure their respective closures.

6. The device of claim 4 wherein said imperforate cover has a central depression in the underside thereof and a marginal base adapted to seat against the top of said web when the dispenser is closed.

7. A unitary molded plastic dispensing device for a container comprising a flat frame member of substantial thickness mountable in one wall of a container, a through opening in said frame having an inner face inclined inwardly toward said container, a bead on said inner face near the top of said opening, a perforated web having a marginal projection extending upwardly therefrom and defining a well, a bead at the top of said well, said web being hinged to one side of said frame and having an inclined outer side wall complementing said inner face and adapted to be removably seated on said inner face beneath the bead on said frame, a tab extending from the side of said web opposite said hinged side for removing the web from the frame, and a removable imperforate cover adapted to fit within said well beneath its bead to seal off said perforated web and hinged to one side of the web.

8. A multiple dispensing closure for the wall of a container comprising a flat frame having a central opening therethrough and, an outwardly directed peripheral groove on said frame, a foraminous closure member hinged to the frame and seatable in said opening in the frame adjacent the plane of the groove, there being an outwardly directed recess in the foraminous member, and an imperforate closure member hinged to the foregoing assembly and seatable in the recess of the foraminous member in substantially the plane of the groove.
